(57) **CLAIM**

The ornamental design for a wedge-shaped gaming machine, as shown and described.

DESCRIPTION

FIG. 1 is a perspective view of a wedge-shaped gaming machine, showing our new design;

FIG. 2 is a bottom view thereof;

FIG. 3 is a front elevational view thereof;

FIG. 4 is a right side elevational view thereof; and

FIG. 5 is a rear perspective view thereof; and,

FIG. 6 is a top view thereof.

Broken lines illustrate features or environmental components that are not part of the design sought to be patented.
